UNITED STATES PATENT OFFICE

170,665

COMBINATION SOFA AND BED

Edmund J. Spence, New York, N. Y., assignor to
 Charlton Company, Inc., Fitchburg, Mass., a
 corporation of Massachusetts

Application May 29, 1952, Serial No. 19,938

Term of patent 7 years

(Cl. D15—11)

To all whom it may concern:

Be it known that I, Edmund J. Spence, a citizen of the United States of America, residing at New York, in the county of New York and State of New York, have invented a new, original, and ornamental Design for a Combination Sofa and Bed, of which the following is a specification, reference being had to the accompanying drawings, forming part thereof.

Fig. 1 is a perspective view of a combination sofa and bed as folded up for a sofa embodying my new design;

Fig. 2 is an elevation of the right hand end of the combination sofa and bed as shown in Fig. 1; and

Fig. 3 is a perspective view of the combination sofa and bed as folded down to form a bed.

I claim:

The ornamental design for a combination sofa and bed, as shown.

EDMUND J. SPENCE.
